CLAIM

The ornamental design for a display screen of a mobile device with a graphical user interface for real-time evaluation, as shown and described.

DESCRIPTION

The patent or application file contains a least one drawing executed in color. Copies of this patent or patent application publication with color drawing(s) will be provided by the Office upon request and payment of the necessary fee.

FIG. 1 is a frontal view of a display screen of a mobile device with a graphical user interface, shown in grayscale; and,

FIG. 2 is a frontal view of a display screen of a mobile device with a graphical user interface, shown in color. The broken line showings of the mobile device are included for the purpose of illustrating environmental structure and form no part of the claimed design.
